UNITED STATES PATENT OFFICE.

ENNIS MUNGER, OF DALLAS, TEXAS.

STOP AND WASTE COCK.

SPECIFICATION forming part of Letters Patent No. 694,880, dated March 4, 1902.

Application filed March 23, 1901. Serial No. 52,592. (No model.)

To all whom it may concern:

Be it known that I, ENNIS MUNGER, a citizen of the United States, residing at Dallas, in the county of Dallas and State of Texas, have invented a new and useful Stop and Waste Cock, of which the following is a specification.

My invention is an improved stop and waste cock; and it consists in the peculiar construction and combination of devices hereinafter fully set forth and claimed.

In the accompanying drawings, Figure 1 is a central sectional view of a stop and waste cock constructed in accordance with my invention. Fig. 2 is a detail elevation of a modified form of the valve. Fig. 3 is a detail sectional view taken through the valve-stem and bushing on a plane indicated by the line *a a* of Fig. 1.

20 The body 1 of the valve is of the usual form of a globe-valve, 2 being the connection of the main pipe, 3 the connection for the water-service pipe, which is to be drained in cold weather to prevent freezing and the bursting 25 of the service-pipe, and 4 being the usual web interposed between the said connections and having the valve-seat 5.

In one side of the body 1 is screwed or otherwise coupled a gland 6, which has the inferiorly-threaded portion 7, the waste-chamber 8, above the same, and a waste-port 9, which communicates with said waste-chamber, and as here shown is formed in a nipple 10, to which a waste-pipe may be connected. 35 The lower or inner end of the gland forms or is formed with a valve-seat 11, which is disposed opposite the valve-seat 5. The said gland 6 is formed with a waste-channel 12 on one side of its screw-threaded bore, which 40 waste-channel establishes communication between the service connection 3 and the waste-chamber 8.

The stem 13, which operates in the gland 6 and has the screw-threaded portion 14, which operates in the threaded bore of said gland, is provided at its lower end with the valves 15 16, which face in opposite directions and are respectively adapted to engage the valve-seats 5 and 11. The said valve-stem 13 is rotated by the usual hand-wheel 17. Any suitable form of handle or a wrench may be employed in lieu of the hand-wheel for operating the valve-stem.

On the outer end of the gland 6 is screwed a 55 cap 18, in which the packing 19 is located and

by which the packing is compressed to prevent leakage around the valve-stem.

The operation of my invention is as follows: When the valve-stem is operated to open the valve 15 from the seat 5 and to close the valve 16 against the valve-seat 11 at the inner end of the gland, as shown in dotted lines in Fig. 1, the water passes freely from the main to the water-service pipe through the connections 2 3, the body of the valve, and the port 65 or seat 5. When it is desired to cut off the service-pipe from the main pipe and to drain the water from the service-pipe to prevent the same from freezing, the valve-stem 13 is turned in such manner as to cause the valve 70 15 to close the port or seat 5. This also causes the valve 16 to open from the seat 11 at the inner end of gland 6, and thereupon establish communication between the waste-port 9 and the connection 3 to the service-pipe, the waste water passing from the latter through the waste-channel 12 into the waste-chamber 8 and from thence through the waste-port 9, as will be understood.

Having thus described my invention, I claim—

In a stop and waste cock, a body having a main and a service connection, a port 5 between the same, and a threaded opening in one side, opposite said port, in combination 85 with a gland having screw-threads at its inner end to engage said threaded opening and thereby detachably couple said gland directly to said body, said gland having a valve-seat 11 formed in its inner end, a threaded bore, a 90 waste-port, and a waste-channel in one side of said threaded bore, said channel connecting said waste-port and said valve-seat 11, a valve-stem, carried by said gland, having a threaded portion engaging the threaded bore 95 of said gland, and an oppositely-faced valve at the inner end of said stem, adapted to alternately close the port 5 and the valve-seat 11, the outer end of said stem projecting through an opening in the outer end of said gland, 100 and a packing-cap screwed on the outer end of said gland, substantially as described.

In testimony that I claim the foregoing as my own I have hereto affixed my signature in the presence of two witnesses.

ENNIS MUNGER.
